UNITED STATES PATENT OFFICE.

JOSEPH J. WESLEY, OF DOUGLASTON, NEW YORK, ASSIGNOR TO METROPOLITAN ELECTRIC & MFG. CO., A CORPORATION OF NEW JERSEY.

METERING PANEL-SWITCHBOARD.

1,119,484.

Specification of Letters Patent.

Patented Dec. 1, 1914.

Application filed July 31, 1913. Serial No. 782,211.

To all whom it may concern:

Be it known that I, JOSEPH J. WESLEY, a citizen of the United States, residing at Douglaston, in the county of Queens and

5 State of New York, have invented certain new and useful Improvements in Metering Panel-Switchboards, of which the following is a full, clear, and exact description.

This invention relates to metering panel 10 switchboards.

The general type of switchboard to which the invention is particularly applicable consists of an insulating base having a plurality of longitudinally disposed permanent 15 conductors, each of which may be connected to any of a plurality of transverse conductors by selective switches mounted on the latter, the transverse conductors being connected to the consumption or load circuits 20 which are usually provided with switches for controlling the same.

One of the objects of the invention is to prevent the operation of the selective switches until the load switches controlling 25 the consumption circuits have been opened, avoiding any danger of arcing between the longitudinally-disposed conductors and the selective switches which might otherwise occur if there were a heavy load on the consumption circuit.

Another object of the invention is to prevent the unauthorized opening and closing of the selective switches and the load terminal switches.

35 With these and other objects in view, my invention consists in means for preventing the opening of each of the selective switches when its corresponding load switch is closed and the closing of the load switch when its 40 selective switch is open and also in means for permanently locking or sealing the selective switches in their open or closed positions, each of which means may be used alone or in combination, the mutual relation 45 between the two means effectually preventing the unauthorized manipulation of the switch board.

In the drawings, I have shown a form of metering panel switch-board for a three-wire system, the general characteristics of which are old but will be described broadly to clearly define the novel features of the present invention.

In the drawings, Figure 1 is a plan of the

panel board, a portion of the board being 55 omitted; Fig. 2 is a side view of Fig. 1; Figs. 3 and 4 are details of the interlocking and sealing means.

Longitudinally-disposed upon a base A of slate, marble or some other insulating material, are the permanent conductors 1 to 14, inclusive, which are suitably mounted on insulating bridges 15. Terminals are provided at one end of each of these conductors whereby the same may be connected to the meter-loops, one of which is shown in Fig. 1.

Arranged immediately above but out of contact with conductors 1 to 14, are a like number of transverse conductors 16, 17, etc. 70 An equal number of consumption circuits are provided which are located on opposite sides of the conductors 1 to 14, one pair of each of the respective sets of terminals being designated 18, 19 and 20, 21. The consumption circuits are alternately connected to the transverse conductors 16, 17, etc., through one of these terminals, as, for example, terminal 18 is connected to conductor 16, and terminal 21 to conductor 17. All of 80 the conductors 16, 17, etc., and their connections to the consumption circuits and longitudinal conductors 1 to 14, are identical. For this reason, the middle portion of the board has been omitted in the drawing 85 and only one circuit on the board will be hereinafter described in detail.

The electric power is supplied to the board through a single-throw three-pole switch 22, each of the outer poles of which are connected by means of bus-bars to a set of terminals 23, 24, and 25, 26, etc., respectively, which correspond in number and position to the terminals 18, 19 and 20, 21, of the consumption circuits. Each of the terminals 23, 24, 25, 26, etc., is adapted to be connected to any of the meter terminals on the ends of the rods 1 to 14, by meter-loops having a meter connected thereto through which the supply of current may be measured. 100 The neutral or middle pole of the switch 22 may be grounded or not as desired, and is connected by a bus-bar 27 to the parallel bus-bars 28 and 29, one side of each of the consumption or load circuits being connected to one of the bus-bars 28, 29 through which a return for the load circuit is afforded. 105

The transverse conductor 17 is preferably rectangular in cross-section and has cylindrical ends forming bearings which are rotatably supported in uprights 30 and 31. A sleeve 32 of conducting material having a square aperture or recess therein, is slidably mounted on the conductor 16 and is constrained to rock or rotate therewith. A contact spring 33 fastened to one side of the sleeve 32 frictionally engages the conductor 17, insuring that these two parts will remain in good electrical contact.

Fastened to the underside of the sleeve 32 are spring contact jaws 36 which are adapted in one position of the conductor 17 to electrically connect the latter to one of the longitudinal conductors 1 to 14, depending upon the position of the sliding sleeve on the conductor 17. The lower ends of one side of the spring-jaws 36 are curved or spread outwardly to form guides to permit the spring jaws 36 to be readily engaged with one of the conductors 1 to 14 when the sleeve is rocked or rotated to contact making position. The part of the sleeve 32 which extends above the conductor 17 is provided with an inclined surface to which is fastened a handle or knob 37 by which the sleeve 32, and therefore the conductor 17, are rocked in a clockwise direction, as will be hereinafter referred to. It will be evident therefore that the sleeve 32 may be slid along the conductor 17 until it is immediately above the longitudinal conductor with which it is desired to make contact, when it may be rocked to make contact between the jaws 36 and the selected longitudinal conductor. These parts therefore constitute a switch which will hereinafter be referred to as the selective switch.

Contact springs 38 electrically connect the conductor 17 to the upright 31, which is connected by a connector 39 to spring-jaws 40 which are connected by one blade of a single-throw switch 41, preferably through a fuse, to the terminal 21 of the load circuit. The other terminal 20 of the load circuit is connected by the other blade of the switch 41 to the spring jaws 42 which are connected to the bus-bar 29 forming the return for the circuit through the neutral of the three-wire system. The switch 41, therefore controls the consumption or load circuit and will be hereinafter referred to as the load switch. It is evident from the preceding description that the consumption circuit or load circuit may be connected by the selective switch to any of the longitudinal conductors 1 to 14; the connection to each of the other consumption circuits being identical.

The end of the conductor 17 extends through the upright 31, as shown in Fig. 3 and is provided with a cap or block 42' of insulating material which fits over its outer end and is firmly secured to it. The upright 31 has fastened thereto an insulating offset part or boss 43 which extends above the top of the upright 31 and is provided with a hole or aperture 44 therein. Interposed between the offset part 43 and the block 42' is a circular disk 45 which is thereby insulated from the upright 31 and the conductor 17, the hole in the disk 45 which fits around the conductor 17 being somewhat larger than the diameter of the same to prevent electrical contact between these two parts. Disk 45 has two lugs 47 and 48, spaced substantially 90° from each other, which have apertures or holes 49 and 50 adapted to register with the aperture 44 when the selective switch is in either its closed or open position. As shown, when the conductor 17 has been turned to bring the spring-jaws 36 into contact with one of the longitudinal conductors 1 to 14, holes 44 and 50 will be in registry. A wire, the ends of which are joined by a lead seal, or indeed any other form of lock, may be passed through the alining apertures 44 and 50 forming a permanent lock. This prevents the selective switch from being rocked out of contact with the selected longitudinal conductor and connected to any other of the longitudinal conductors which would permit the connecting of the load circuit to the meter of another tenant. When the selective switch has been turned to open position, the holes 49 and 44 will be in registry and the switch may be locked or sealed in this position in the manner already described. In order to change the position of the selective switch, it is therefore necessary to break this lock or seal, which will give notice to the electrical company that the board has been tampered with.

Preferably integral with the disk 45 is an L-shaped blade 51 bent at right angles to the disk, and extending to a position in close proximity to a handle 52 of the load switch 41 when the selective and load switches are in their closed position. (See Fig. 4.) This blade 51 forms an effective lock between these two switches, for, if an attempt is made to rock the selective switch to open position in a clockwise direction as viewed in Fig. 4, the blade 51 will abut against one end of the handle 52 and prevent the selective switch from being opened prior to the opening of the load switch. If an attempt is made to rotate the sleeve 32 in a counter clockwise direction the free extremity of the knob or handle 32, since the same is arranged at a considerable angle to the vertical when the switch is in its normally closed position, will abut the conductor 13 before the switch blades are entirely disengaged from the same and the opening of the switch prevented. The transverse conductor 17 is therefore always dead before the selective switch may be operated, and for this reason

the danger of arcing between the spring-jaws 36 and the longitudinal conductor to which it is connected is entirely eliminated. When the selective and load switches are in their open position, the L-shaped blade 51 will be directly over the spring-jaws 40 adapted for contact with the load switch 41, which will prevent the load switch 41 from being closed prior to the closing of the selective switch. It will thus be seen that during the manipulation of the selective switch the transverse conductor 17 on which it is mounted, is always dead and the danger of injuring the conductors when there is a heavy current passing through the load circuits is entirely overcome. Moreover, if the transverse conductor 17 is locked with its corresponding selective switch in open position, it is impossible for a tenant or other person to connect the load in circuit by using a connector between the transverse conductor 17 and one of the longitudinal conductors, as the load circuit still remains open at the load switch, which switch cannot be closed due to the interposition of the L-shaped blade 51 between the spring-jaws 40 and the blade of the load switch 41, thus safe-guarding the board against the unwarranted use of current. The interlocking mechanism and permanent locking means between each of the other selective switches and load switches are similar and will not be described.

While I have shown my invention in connection with a panel switchboard for a three-wire system, yet it is not my intention to be limited to this specific form, as the invention is equally applicable to switchboards using a two-wire system and to other uses within the scope of the appended claims.

Having described my invention, I claim:

1. In a panel switchboard, an insulating base, a plurality of permanent conductors thereon, load switches, means including a selective switch for electrically connecting each of said load switches to any of said permanent conductors, and means for preventing the opening of each selective switch when its corresponding load switch is closed and the closing of the load switch when its selective switch is open.

2. In a panel switchboard, an insulating base, a plurality of permanent conductors arranged longitudinally and transversely thereon, the transverse conductors being rotatable, slidable selective switches on each of said transverse conductors, constrained to rotate therewith, a plurality of load switches one for each of the transverse conductors, and means for preventing the opening of each selective switch when its corresponding load switch is closed and the closing of the load switch when its selective switch is open.

3. In a panel switchboard, an insulating base, a plurality of permanent conductors arranged longitudinally and transversely thereon, the transverse conductors being rotatable, slidable selective switches on each of said transverse conductors, constrained to rotate therewith, a plurality of load switches one for each of the transverse conductors, and means comprising a blade fixed to the end of each of the transverse conductors and abutting a part of the load switch for preventing the opening of the selective switch in one direction when the load switch is closed and the closing of the load switch when the selective switch is open.

4. In a panel switch board, an insulating base, a plurality of permanent conductors thereon, load switches, means including a selective switch for electrically connecting each of said load switches to any of said permanent conductors, and means for permanently locking each of said selective switches in its connected or disconnected position.

5. In a panel switchboard, an insulating base, a plurality of permanent conductors thereon, load switches, means including a selective switch for electrically connecting each of said load switches to any of said permanent conductors, means for preventing the opening of each selective switch when its corresponding load switch is closed and the closing of the load switch when its selective switch is open, and means for permanently locking each of said selective switches in its connected or disconnected position.

6. In a panel switchboard, an insulating base, a plurality of permanent conductors arranged longitudinally and transversely thereon, said transverse conductors being rotatable, selective switches slidably mounted on each of said transverse conductors for connecting each of the transverse conductors to any of the longitudinal conductors, and means for permanently locking each of said transverse conductors and its corresponding selective switch in connected or disconnected relation to any of the longitudinal conductors.

7. In a panel switchboard, an insulating base, a plurality of permanent conductors arranged longitudinally and transversely thereon, said transverse conductors being rotatable, selective switches slidably mounted on each of said transverse conductors for connecting each of the transverse conductors to any of the longitudinal conductors, a plurality of load switches one for each of said transverse conductors, means for preventing the opening of each of the selective switches when its corresponding load switch is closed and the closing of the load switch when its selective switch is open, and means for permanently locking each of said transverse

conductors and its corresponding selective switch in connected or disconnected relation to any of the longitudinal conductors.

8. In a panel switchboard, a conductor having standards for rotatably supporting the same, a disk adjacent one of said standards and constrained to move with said conductor, said disk having a plurality of apertures therein, a corresponding aperture in said standard, and means for locking said conductor against rotation passing through the aperture in said standard and one of the apertures in said disk.

9. In a panel switchboard, a switch, a rotatable conductor electrically connected thereto, and a blade rigidly mounted on said conductor arranged in close proximity to said switch for preventing the rotation of the conductor in one direction when said switch is closed.

In witness whereof, I subscribe my signature, in the presence of two witnesses.

JOSEPH J. WESLEY.
